UNITED STATES PATENT OFFICE.

THEODORE WETZEL, OF SAN FRANCISCO, CALIFORNIA.

OIL BURNER.

1,242,291.

Specification of Letters Patent. Patented Oct. 9, 1917.

Application filed August 16, 1916. Serial No. 115,169.

To all whom it may concern:

Be it known that I, THEODORE WETZEL, a citizen of the United States, residing at San Francisco, in the county of San Francisco, State of California, have invented a new and useful Oil-Burner, of which the following is a specification in such full and clear terms as will enable those skilled in the art to construct and use the same.

10 This invention relates to an internal mixing oil burner having means for increasing or diminishing the quantity of oil burned while the oil is at all times completely and thoroughly mixed with the steam whereby 15 it is perfectly atomized when it issues from the nozzle.

It will be understood by those skilled in the art that while many burners will work properly under a given steam and oil pressure that they do not work well when the 20 quantity of steam or oil is reduced, making it very difficult to regulate the fire produced by them.

With the present invention means is provided for varying the size of the mixing chamber whereby an increased or decreased 25 quantity of oil will be properly mixed.

The result of the mixing and atomization 30 of the oil at different oil and steam pressures is that the oil is burned without a carbon deposit at the burner tip and no heavy black smoke.

An embodiment of the invention is shown 35 in the drawing in which the same reference numeral is applied to the same portion throughout, but I am aware that there may be many modifications thereof,

Figure 1 is a side elevation partly in section of the complete burner, the line of section being indicated on Fig. 7,

Fig. 2 is a vertical sectional view of the burner adjacent the slidable steam supply pipe,

Fig. 3 is a front elevation of the burner 45 tip,

Fig. 4 is an end elevation of the burner looking toward the furnace, the adjusting wheel being removed,

Fig. 5 is an end view of the front mixer,

Fig. 6 is a side elevation of the mixer showing the front and rear members thereof,

Fig. 7 is an end elevation of the rear mixer, and

Fig. 8 is a plan in section of the burner 55 tip.

The burner is assembled on a circular

plate 1 into which a pipe 2 and a nipple 3 are threaded, the pipe 2 having a suitable connection 3' and 4 for the supply of steam to the burner.

Secured on the front of the plate 1 is a plate 4 having bosses 5 and 6 in which the slidable sleeves 7 and 8 are seated, whereby packing glands are formed around the two slidable steam pipes 9 and 10, a return bend 60 65 connecting said pipes while a plate 12 is also connected therewith and has a lug 13 through which a long screw 14 passes. The screw has a portion 15 turned down small to pass through a block 16 and short tube 17 70 which allow the screw to turn in the lug 13 to adjust the position of the steam pipes and mixing nozzle in the mixing chamber. The hand wheel 18 is secured on the screw with a pin 19. A U bolt 20 rigidly connects 75 the return bend and plate 12.

The nipple 3 has a T 22 connected therewith into the lower side of which the oil supply pipe 23 is connected. A pipe 24 is also connected with the T 22 and it has a 80 socket 25, bushing 26, nipple 27 and burner tip 28 on its end.

The pipe 10 extends into the pipe 24 forming the internal mixing chamber and it carries the mixing nozzle 29 on its end, said 85 nozzle having a series of spiral grooves 30 and a plurality of openings 31, 32 for the escape of the steam. On the front of the mixing nozzle 29 there is a mixing head connected thereto with a threaded rod 33 provided with two oppositely placed conical skirts 34, 35, the former having a plurality 90 of openings therethrough.

In operation the steam passes to the burner from the pipe 10, escapes to the mixing 95 chamber through the holes 31, 32, and through the holes in the member 34 thereby effectually mixing the oil in the chamber adjacent 25, 26 and 27. The steam being under considerable pressure and whirling rapidly completely breaks up the oil before it passes out of the tip 28, said tip having an opening suited to the particular type of flame desired.

When it is desired to increase the flame 105 the supply of oil and steam is increased and the steam nozzle is pulled back to increase the size of the mixing chamber, and the reverse operation is gone through with when a smaller flame is desired.

Having thus described my invention what I claim as new and desire to secure by Let-

ters Patent of the United States, is as follows, express reservation being made of permissible modifications:

1. An oil burner comprising a burner pipe forming a mixing chamber, a steam pipe slidable into said mixing chamber, means to adjust the position of said steam pipe, a steam nozzle on the end of the steam pipe within the mixing chamber, and a double 10 conical tip forming means for mixing the steam and oil in front of the steam nozzle and secured thereto.

2. An oil burner comprising a burner pipe forming a mixing chamber, oil and steam

supply pipes therefor, a pair of packing 15 boxes, a U shaped steam pipe extending into both of said packing boxes for supplying steam to the mixing chamber, a steam nozzle having spiral passageways on the steam pipe within the mixing chamber, and means 20 to move the steam pipe longitudinally of the pipe forming the mixing chamber to increase the size of the mixing chamber several times over its minimum size, and a tip on the end of the burner pipe.

25

In testimony whereof I have hereunto set my hand this 8th day of August A. D. 1916.

THEODORE WETZEL.
